(57) CLAIM

An ornamental design for the secondary gaming console, as shown and described.

DESCRIPTION

FIG. 1 is a front view of a secondary gaming console, showing my new design;

FIG. 2 is a side view of FIG. 1; and,

FIG. 3 is a top view of FIG. 1.

FIG. 4 is a front view of a secondary gaming console, showing a second embodiment thereof;

FIG. 5 is a side view of FIG. 4; and,

FIG. 6 is a top view of FIG. 4.

The broken line showing of the primary game console is for illustrative purposes only, and forms no part of the claimed design.
